(57) **CLAIM**

The ornamental design for an oblong harness square, as shown and described.

DESCRIPTION

FIG. 1 is a perspective view of an oblong harness square, showing my new design from above;

FIG. 2 is a top plan view thereof;

FIG. 3 is a front elevation thereof;

FIG. 4 is a left side view thereof;

FIG. 5 is a rear elevation thereof;

FIG. 6 is a right side view thereof; and

FIG. 7 is a bottom plan view thereof.

FIG. 8 is a perspective view of a second embodiment of an oblong harness square showing my new design;

FIG. 9 is a top plan view thereof;

FIG. 10 is a front elevation thereof;

FIG. 11 is a left side view thereof;

FIG. 12 is a rear elevation thereof;

FIG. 13 is a right side view thereof; and,

FIG. 14 is a bottom plan view thereof.
